UNITED STATES PATENT OFFICE.

MARCELLE M. MARQUIS, OF NEW YORK, N. Y., ASSIGNOR TO CAMLIN CORSET CO. INC.,
A CORPORATION OF NEW YORK.

LADY'S UNDERGARMENT.

Application filed June 23, 1926. Serial No. 117,949.

This invention relates to improvements in undergarments and has particular reference to improvements in ladies' undergarments known as combined brassières and corset or 5 corselettes.

The object of the invention is to provide a novel, useful and generally improved garment of this character, including novel features for providing abdominal supporting 10 means and an especially well fitted garment including a brassière portion.

With these objects in view the invention is embodied in a lady's undergarment arranged and constructed as hereinafter set 15 forth and as illustrated in the accompanying drawing in which

Fig. 1 is a view of the outside of the garment opened up flat.

Fig. 2 is a perspective view of the garment 20 partially closed.

Fig. 3 is a view of the garment fully closed.

Fig. 4 is a detail view illustrating the closing means or special arrangement of the 25 hooks and eyes.

Referring to the drawing, the garment comprises a back corset portion 5 of corset material, usually brocaded silk or the like, and provided with boning or corset bones 30 6, 6 below the waist line 7.

To each side of the back portion there is attached a side portion numbered respectively 8 and 9. The left side portion 8 consists of an upper brassière portion 10 preferably made of knitted silk or like fabric, to which is secured a lower left hip portion 11 of elastic material.

As more particularly seen in Figure 4, the left side portion 8 is provided with a tape 40 12 extending the length of the garment, and to this tape are sewed eyelets 13. In addition, the left side portion is provided with a stiffening insert 14.

The upper part of the insert 14 is provided with a tape 15 provided with eyelets 16 which are spaced and placed to correspond with such of the eyelets 13 as are placed in similar vertical spaced position on the tape 12. The arrangement is such, 50 that when the garment is closed, the eyelets 16 form a continuation in spacing and position of the lower eyelets 13. This is clearly seen in Figure 1.

The right side portion 9 is symmetrical 55 with the left side portion 8 and consists

also of a lower elastic portion 18 and an upper brassière portion 19 of knitted fabric.

To the right side edge 20 of the right side 60 9 there is attached a front flap or front brassière portion 21 made entirely of knitted fabric and which extends to about half way between the waist line and the bottom edge of the garment. This front portion is provided with light boning 22.

The lower portion 23 of the front portion 21 forms an inner abdominal support when the garment is closed. To this end, therefore, the front portion 21 is provided with hooks 25 which are hooked into the eyelets 13, see Figures 2 and 4 to close the upper 70 part of the garment.

In addition, a front corset portion 26 of usual corset material is attached to the edge 20 and extends from the waistline down to the bottom edge of the garment. The front 75 corset portion 26 is provided with an elastic insert 27 and light boning 28. It is provided with hooks 29 which hook into the eyelets 16 and the lower eyelets 13. Hence the reason for the accurate and identical 80 spacing of the eyelets 16 and 13.

When the portion 26 is closed as in Figure 3 it completes the garment and securely keeps the abdominal support 23 in place and flat. In fact, it provides a second abdominal supporting portion.

It will be seen, therefore, that the garment according to this invention provides an upper brassière portion and a lower corset portion with special abdominal supports. 90 Also that perfect alinement and good fit is assured because of the one piece tape 12 to which both edges of the inner and outer front portion are hooked. The upper overlapping portion of the front 26 is hooked 95 into the eyelets 16. In this manner a perfect fit vertically is obtained and a smoothly fitting corset is provided by reason of the elastic hip portions. The upper portions form a brassière, which fits comfortably 100 around the body.

I claim:-

1. A lady's undergarment forming a combined brassière and corset comprising in combination, a back portion and two side portions secured together, each of said side portions consisting of a lower elastic hip portion and an upper brassière portion, a front brassière portion of less length than the said three portions secured to the right 110

- edge of the right side portion and provided with boning in its lower part whereby to form an abdominal support, hooks on the free edge of the front brassière portion 5 adapted to engage eyes on the free edge of the left side portion for closing the brassière of the garment, a front corset portion secured to the right edge of the said right side portion and overlapping in a vertical direction the said abdominal supporting part, 10 additional eyelets secured to the left side portion and spaced to correspond with the eyelets thereon aforesaid and hooks on the free edge of the front corset portion spaced 15 to engage the eyelets on the left edge of the left side portion and the said additional eyelets for closing the corset of the garment on the outside of the brassière of the garment.
- 20 2. A lady's undergarment comprising an upper brassière portion and a lower corset portion including a brassière front portion of less length than the garment, a corset front portion of less length than the garment and overlapping the lower part of the brassière front, a first row of eyelets on the left free edge of the garment some of which first eyelets are adapted to be engaged by hooks on the free edge on the said brassière 25 front portion to close the same, a second additional row of eyelets secured adjacent the said left free edge of the garment, which second row of eyelets together with the remaining unhooked first named eyelets are adapted to be engaged by hooks on the said corset front portion to close the same. 30
3. A lady's undergarment forming an upper brassière portion and a lower corset portion, each of said portions including a separate front part, the said two front parts 35 overlapping each other in a vertical direction, and each of said front parts having a free closing edge, hooks in the said two closing edges, a tape extending the length of the garment at the extreme left edge 40 thereof, a tape insert in said extreme left edge overlapping a portion of the said full length tape, eyelets in the latter and in the said tape insert, some of the eyelets in the said full length tape being adapted to be 45 engaged by all the hooks in the closing edge of the brassière portion, and the balance of said eyelets in the full length tape together with the eyelets in the said tape insert being adapted to engage all of the hooks 50 in the closing edge of the corset portion. 55

MARCELLE M. MARQUIS.
